Primary Examiner — Rhea Shields(74) *Attorney, Agent, or Firm* — Christopher A. Rothe; CM Law(57) **CLAIM**

The ornamental design for an infusion filter, as shown and described.

DESCRIPTION

FIG. 1 is a perspective view of an infusion filter according to one embodiment;

FIG. 2 is a top view thereof;

FIG. 3 is a bottom view thereof;

FIG. 4 is a left side view thereof;

FIG. 5 is a front view thereof;

FIG. 6 is a right side view thereof; and,

FIG. 7 is a rear view thereof.

The broken lines shown in the drawings are for the purpose of illustrating unclaimed portions of the infusion filter, and form no part of the claimed design.
